UNITED STATES PATENT OFFICE.

TITUS S. HOSE, OF LITTLE FALLS, NEW YORK.

HAMMER.

1,362,797.

Specification of Letters Patent. Patented Dec. 21, 1920.

Application filed April 26, 1920. Serial No. 376,625.

To all whom it may concern:

Be it known that I, TITUS S. HOSE, a citizen of the United States, residing at Little Falls, in the county of Herkimer and 5 State of New York, have invented a new and useful Improvement in Hammers, of which the following is a specification.

This invention relates to improvements in hammers of the type known as nail or 10 claw hammers, in which the hammer head is provided at one side of the handle with a striking end or portion and at the opposite side of the handle with a nail-pulling claw having a tapering slot to engage the 15 head end of a nail for pulling the same.

The object of the invention is to adapt the hammer, by means of an exceedingly simple and inexpensive improvement or 20 change in the hammer head, for use as a convenient and efficient tool for splicing or joining wires or mending wire fences.

In the accompanying drawings:

Figure 1 is a side elevation of a hammer illustrating the use of the same for joining the ends of two wires.

Fig. 2 is an end elevation of the hammer head.

Fig. 3 is a fragmentary side elevation of the hammer showing the head partly in 30 section.

The hammer is constructed like the ordinary nail or claw hammer except that the neck of the striking portion of the head is provided with a hole extending through the 35 same in a direction lengthwise, or substantially lengthwise, of the hammer, and in which hole a wire is adapted to be inserted and secured.

10 represents the metal head of the hammer and 11 the handle which, as usual, is 40 preferably made of wood and secured in a socket in the head between the ends thereof, the head being preferably provided with an add-eye socket having a projecting portion 45 12 which embraces the handle for a considerable distance so as to form a long bearing for the handle and enable the handle to be used as a lever in the use of the tool without danger of loosening the handle. 13 50 is the striking end or portion of the head and 14 the slotted or forked nail-pulling claw, said striking end and claw being disposed at opposite sides of the handle socket.

The claw is preferably of the usual curved 55 wedge shape with a tapering, sharp-edged

slot to receive the head end of a nail for pulling the latter.

15 is the wire-receiving hole in the striking end or portion of the hammer head. This hole is preferably round and drilled 60 through the neck of the striking end, and extends lengthwise of the hammer or substantially parallel with the handle socket. This hole is large enough for the free passage through the same of a barbed or other 65 wire, such as used in the construction of fences or other wire structures, but is not large enough to appreciably weaken the head. The hole does not in anywise interfere with the ordinary use of the tool as a 70 hammer.

When using the hammer for splicing the ends of a fence wire, or joining the ends of two wires, a loop 16 is formed at the end of one of the wires 17 and the end of the 75 other wire 18 is passed through the loop. This end of the wire 18 is then inserted through the wire hole 15 in the hammer and is secured by bending the end of the wire or twisting it one or more turns around the 80 neck of the hammer. Then the wire 18 is drawn as tight as possible through the loop 16 by pulling on the hammer, and the forked claw is placed so as to straddle the body portion of the wire 18, as shown in Fig. 1. 85 The tapering or wedge-shaped slot of the claw will bite the wire and serve as a fulcrum for the hammer so that by pushing the end of the hammer handle downwardly or toward the wire 18, the end of the wire 90 18 will be drawn taut through the loop 16. The end of the wire 18 can then be secured by turning the hammer so as to twist the end about the body of the wire 18, after which the end of the wire is disengaged from the 95 wire hole 15 in the hammer.

Since the wire hole 15 extends through the neck substantially midway between the sides of the hammer head and substantially lengthwise of the hammer, the strain 100 incident to tightening the wire is placed centrally on the hammer, or in the plane of the body of the wire and there is no tendency to deflect the hammer sidewise, and the hammer forms an exceedingly efficient 105 and simple tool for splicing or joining wires.

I claim as my invention:

1. A hammer - like tool comprising a handle, and a head having a neck portion 110

- and a forked claw extending to opposite sides of the axis of the handle, said head having a hole for the reception of a wire extending through said neck portion in a direction substantially lengthwise of the handle.
2. A hammer - like tool comprising a handle, and a head having a projecting handle-receiving socket, and a neck portion and a forked claw projecting to opposite sides of the handle socket, said head having a hole for the reception of a wire extending through said neck portion in a direction substantially parallel with said handle socket.
3. A tool comprising a head having a

forked claw extending from one side thereof, and a neck portion extending from the other side of said head, and a handle-receiving socket projecting from said head between said claw and neck portions, said neck portion having a diametrically disposed hole therethrough extending in a direction substantially lengthwise of the axis of said socket.

Witness my hand this 19th day of April, 1920.

TITUS S. HOSE.
